UNITED STATES PATENT OFFICE.

JOSEPH P. CROWLEY, OF TOLEDO, OHIO, ASSIGNOR TO THE LIBBEY-OWENS SHEET GLASS COMPANY, OF TOLEDO, OHIO, A CORPORATION OF OHIO.

APPARATUS FOR MAKING CONTINUOUS SHEET GLASS.

Application filed March 24, 1919. Serial No. 284,708.

To all whom it may concern:

Be it known that I, JOSEPH P. CROWLEY, a citizen of the United States, residing at Toledo, in the county of Lucas and State of Ohio, have invented a new and useful Improvement in an Apparatus for Making Continuous Sheet Glass, of which the following is a specification.

My invention relates to improvements in making sheet glass in which a shell or cylinder of noncorroding metal is used to bend the sheet from a vertical to a horizontal position, said cylinder being driven or rotated by frictional means, said means consisting of power driven shafts, two or more in number, extending through the above cylinder and pressing against the inside of said cylinder, as shown in the accompanying drawing. The objects of my improvement are first to provide a means to assist the sheet as it is drawn so as to reduce the stretching and shredding of the glass when in a horizontal position, second, to provide large openings on each end of the cylinder for injecting a cooling fluid whenever and wherever required, and third, to provide an even and regular pull to the sheet so that the drawing strain is free and not jerky.

I attain these objects by the mechanism illustrated in the accompanying drawings, in which—

Fig. 1 shows a longitudinal section thru the apparatus on line 1—1 of Fig. 2.

Fig. 2 is a transverse vertical section of the apparatus showing a longitudinal section thru the cylinder and drivers on line 2—2 of Fig. 1.

Referring to Fig. 1, the hollow cylinder 4, is mounted on the drive shafts or rolls 5, four such shafts being shown but two or more could be used. The drive shafts 5, are mounted in suitable bearings 10, and have shoulders 11, which allow the cylinder 4, to float within predetermined limits. The gears 7, are non-rotatably mounted on the ends of shafts 5, and are driven by means of gear 8, secured to the power driven shaft 9. Beyond the cylinder are rollers 6, which are power driven and afford the necessary draught to carry the sheet 3, on thru a lehr. The sheet 3, is drawn from a mass of molten glass 2, which is contained in the tank 1, and bent over the cylinder or roller 4, and carried away on the rollers 6.

Those familiar with the art, are aware of the importance of keeping this bending means cool enough to avoid shredding the glass. To avoid both has been a very difficult problem and requires the closest attention. By using this type of apparatus, one may readily detect the hot and cold spots in the cylinder and can apply the cooling fluid accordingly. By making the cylinder 4 as big as possible and supporting it on drive rolls 5, as shown in Figs. 1 and 2, large openings are formed which can easily admit any cooling fluid, means or apparatus necessary to regulate the temperature required at this point to insure the best results on the sheet of glass 3. Shredens are sometimes caused by scratching due to the glass slipping on a hard metal surface. With this apparatus, the glass can travel with the floating cylinder 4, and all slipping would take place between the cylinder 4, and the drive shafts 5. This would avoid scratches and other defects caused by slippage between the sheet of glass and the metal cylinder.

I have not shown or described in detail a complete continuous drawing apparatus but only that portion thereof which carries and bends the sheet from a vertical to a horizontal plane. Any suitable form of mechanism for applying draught to the sheet and maintaining the width thereof could be used with the bending device forming the subject matter of this invention.

Having described my invention what I claim is:

1. In an apparatus for drawing continuous sheet glass, a bending device for the sheet, comprising a rotatable drum, and roller supporting means for the drum through which means the drum is frictionally driven.

2. In an apparatus for drawing continuous sheet glass, a bending device for the glass sheet comprising a hollow cylindrical drum and means located interiorly of the drum for frictionally supporting and rotating said drum.

3. In an apparatus for drawing continuous sheet glass vertically from a molten mass and then bending the sheet into a horizontal plane, a bending device comprising a hollow metallic drum and means located partially within the drum for frictionally supporting and rotating the drum.

4. In an apparatus for drawing continuous sheet glass, a bending device for the sheet comprising a hollow metallic cylinder, a plurality of drive shafts within the cylinder frictionally contacting and supporting the same and means for supporting the drive shafts.
5. In an apparatus for drawing continuous sheet glass, a bending device for the sheet, comprising a tubular metal roller, and supports rotating on fixed axes and engaging the inner surface of the tube at spaced intervals, so that large portions of the ends of the roller are always open and never occupied by any rotating parts, whereby non-rotary cooling devices may be inserted and applied locally to the interior of the tube.
6. In an apparatus for drawing continuous sheet glass, a bending device comprising a hollow metallic drum over which the sheet is bent, a plurality of spaced drive shafts within the drum frictionally supporting and driving the same, and bearings for supporting the drive shafts, the contacting surfaces of the glass sheet and drum be-

ing more extensive than the contacting surfaces of the drum and drive shafts.

7. In an apparatus for drawing continuous sheet glass a bending device comprising a hollow floating cylinder over which the glass sheet is bent and roller means for supporting the cylinder, and frictionally rotating the same in the direction of travel of the sheet.

8. In apparatus for drawing sheet glass, the combination of a roll for changing the direction of the sheet of glass being drawn, and a second roll disposed in supporting contact with the said first-named roll but not in contact with the glass sheet.

9. In apparatus for drawing sheet glass, the combination of a roll for changing the direction of the sheet of glass being drawn, and a second roll disposed in supporting contact with the said first-named roll throughout substantially its entire length but not in contact with the glass sheet.

JOSEPH P. CROWLEY.
